[57] CLAIM

The ornamental design for a hedge trimmer, as shown and described.

DESCRIPTION

FIG. 1 is a right side elevational view of a hedge trimmer embodying our design;

FIG. 2 is a left side elevational view thereof;

FIG. 3 is a top plan view thereof;

FIG. 4 is a bottom plan view thereof;
FIG. 5 is a rear elevational view thereof;
FIG. 6 is a front elevational view thereof;
FIG. 7 is a right side perspective view thereof;
FIG. 8 is a left side perspective view thereof;
FIG. 9 is an enlarged right side elevational view of an engine portion thereof;
FIG. 10 is an enlarged right side elevational view of a handle portion thereof;
FIG. 11 is an enlarged right side elevational view of a blade portion thereof;
FIG. 12 is an enlarged left side elevational view of an engine portion thereof;
FIG. 13 is an enlarged left side elevational view of a handle portion thereof;
FIG. 14 is an enlarged left side elevational view of a blade portion thereof;
FIG. 15 is an enlarged top plan view of an engine portion thereof;
FIG. 16 is an enlarged top plan view of a handle portion thereof;
FIG. 17 is an enlarged top plan view of a blade portion thereof;
FIG. 18 is an enlarged bottom plan view of an engine portion thereof;
FIG. 19 is an enlarged bottom plan view of a handle portion thereof;
FIG. 20 is an enlarged bottom plan view of a blade portion thereof;
FIG. 21 is an enlarged rear elevational view thereof; and,
FIG. 22 is an enlarged front elevational view thereof.
FIGS. 7 and 8 are shown in a detached manner for ease of illustration. The remaining views of the claimed article have been shown separately for clarity of illustration.
